UNITED STATES PATENT OFFICE.

THEODORE J. BENDLAGE, OF MARSHALLTOWN, IOWA.

SANITARY HEATED STOCK-FOUNTAIN.

1,301,805.

Specification of Letters Patent. Patented Apr. 29, 1919.

Application filed December 4, 1916. Serial No. 135,065.

To all whom it may concern:

Be it known that I, THEODORE J. BENDLAGE, a citizen of the United States of America, and resident of Marshalltown, 5 Marshall county, Iowa, have invented a new and useful Sanitary Heated Stock-Fountain, of which the following is a specification.

The object of this invention is to provide 10 an improved construction for stock fountains and particularly that class of fountains especially adapted for watering hogs, sheep and other small animals.

A further object of this invention is to 15 provide improved means for heating the contents of a trough and drinking cups or trays therein so as to maintain the water at a temperature above the freezing point.

A further object of this invention is to 20 provide improved means for dividing a trough into drinking spaces and supplying separate drinking cups or trays in said spaces.

A further object of this invention is to 25 provide spaced trays or drinking cups in a common trough, said trays or drinking cups being removable and replaceable by vertical movement relative to the trough and being adapted to receive water from the trough, 30 said drinking cups or trays being open and convenient of access by small animals.

A further object of this invention is to 35 provide an improved construction for a drinking cup or tray having a sediment chamber adapted to receive settling from water and means for draining the same.

A further object of this invention is to 40 provide improved means for partially covering, confining and holding separate drinking cups or trays in a common trough.

My invention consists in the construction, 45 arrangement and combination of elements hereinafter set forth, pointed out in my claims and illustrated by the accompanying drawing, in which—

Figure 1 is a plan of the complete device in position for practical use. Fig. 2 is a side elevation, partly in section, of the same. Fig. 3 is a cross-section through the device 50 between the separate drinking cups, on the indicated line 3—3 of Fig. 2. Fig. 4 is a cross-section on the indicated line 4—4 of Fig. 2. Fig. 5 is an end elevation of the device.

In the construction of the device as shown 55 the numeral 10 designates generally a cabi-

net or frame preferably a quadrilateral parallelepipedon in shape. The cabinet or frame 10 preferably is formed of sheet metal such as galvanized iron and may be constructed without a bottom if desired. The cabinet or frame is provided with a horizontal partition 11 extending transversely thereof approximately midway between its top and bottom. Portions of the top of the cabinet or frame 10 are omitted at each side of a central strip 12 extending transversely thereof and the upper margins of the sides of the frame are bent outwardly at the sides of said open spaces to form flanges 13. A trough 14, concavo-convex in cross-section, except at its center, is mounted rigidly in the frame or cabinet 10 above the partition 11 and extends from one end 10^a of the frame to a point adjacent to the opposite end 10^b of said frame, there being a space 15 provided adjacent to the end 10^b for the circulation of air as hereinafter described. The trough 14 extends beneath the transverse strip 12 and may be secured in any desired manner to the frame or cabinet and the end wall 10^a of said frame may form one end portion of said trough. A groove, square in cross-section, is formed in, centrally and longitudinally of the bottom of the trough 14 and forms a sub-trough or bulb 16 extending from end to end of the trough and adapted to receive and contain sediment such as settling from water in said trough and prevent the same being agitated and stirred up by animals drinking or otherwise moving the water or fountain. This sub-trough tends to clarify the drinking water at rest before the same enters the drinking cups or trays hereinafter described. A plugged drainage port is provided at one end of the sub-trough 16 and normally is closed by a stopper 17 extending through the end wall 10^a. The sub-trough 16 serves as the lower portion of a partition centrally of the space immediately above the partition 11 and divides said space generally into two longitudinal compartments communicating across the end of the trough through the space 15, said sub-trough being in contact with the partition 11. A water supply pipe 18 extends from beneath the fountain and centrally thereof through the partition 11 and is provided with a suitable valve such as is indicated by the numeral 19 and controlled by a float 20, by means of which flow of water from said pipe to the trough

is regulated and governed by the depth of water in the trough. A door 21 may be provided in the lower portion of the end wall 10^a of the cabinet or frame and a lamp 22 is located within the lower portion of the cabinet or frame and has its chimney extending through a hole 23 in the partition 11 near one end of said partition. Ventilating ports 24 may be provided in the end wall 10^a or door 21 as desired to provide for the entrance of air to the interior of the frame or cabinet. Air egress ports 25 also are formed in the end wall 10^a and near the upper portion thereof. It should be observed that the hole 23 around the chimney of the lamp 22 communicates with one end portion of the air space on one side of the sub-trough 16 and the egress ports open outward from the same end portion of the air space on the opposite side of said sub-trough. Therefore, draft created by combustion in the lamp causes a current of air through the ports 24 to the lower chamber of the frame, wherein it is heated somewhat, thence through the hole 23 and along the bottom of the trough and one side of the sub-trough to and thence through the air space 15 across the opposite end of the trough and thence along the opposite space to and through the exit ports 25. During such travel the air commingles with products of combustion from the lamp and is heated partially by such commingling and partially by radiation from the lamp and said air, so heated, warms the water in the trough 14 and maintains it at a temperature above freezing, such temperature being determined by atmospheric temperature and the power of the lamp. Drinking cups or trays 26, 27, alike in construction, are mounted in the open spaces of the top of the cabinet or frame 10 at each side of the central strip 12, and extend from said strip to the end walls of the frame. The trays preferably are made of sheet metal such as galvanized iron and are concavo-convex in cross-section except at their centers, and side margins of the bottom of each tray are extended outwardly to form flanges 28 adapted to rest on the flanges 13 of the frame. Covers 29, 30, also formed of sheet metal, are constructed with hook flanges 31 on their side margins adapted to embrace and slidably engage the side flanges 13 and 28 of the frame and drinking cups or trays respectively and bind them together. The covers 29, 30 are formed with openings of suitable size and shape 32 through which access may be had from above to the drinking cups or trays for drinking by small animals such as swine. Each drinking cup or tray 26, 27 is formed with a central longitudinal depression, groove, duct or bulb 33 parti-circular in cross-section and having an opening at one end through one end wall

of the tray adapted to be closed by a stopper 34. The depression or bulb 33 extends within, but does not entirely close, the sub-trough 16 and serves to receive and contain sediment such as settling from water in the 70 cup or tray. The drinking cups or trays 26, 27 are mounted end to end and spaced apart on opposite sides of the central strip 12 and each tray is formed with water ingress ports 35 in the end thereof nearest to the 75 center of the fountain and below the upper margins of the end of the trays, which ports are covered with strainers 36 preferably made of cloth stretched across said ports. The covers 29, 30 are removable and 80 replaceable by horizontal movement longitudinally of the frame and the drinking cups or trays 26, 27 are removable and replaceable, when said covers are removed, by vertical movement relative to the trough 85 14. The sediment received in the depressions 33 may be drained out through the port closed by the stopper 34, and consists of settling from the water, deposited in the trays by animals drinking therefrom or in any other manner.

It will be observed that the supply of water in the trays, through the strainer-covered ports 35, is determined by the height of water in the trough 14 governed by the 95 float-controlled valve 19.

It will be observed that the water in the cups or trays is maintained at desired temperature by convection through water in the trough, the latter being heated as above 100 described.

I do not desire to be understood as limiting myself to the exact construction and arrangement of parts shown and described as the same may be modified in many particulars without departing from my invention.

I claim as my invention:

1. A sanitary heated stock fountain comprising a suitable sheet metal frame formed with a horizontal partition whereby the frame is divided into horizontal compartments, said frame being formed with a door in one end of its lower compartment and ventilating ports in said door, said frame also being formed with egress ports in the 110 adjacent end wall of its upper compartment, the partition being formed with a flue-hole adjacent said door and at one side of the center of said partition, whereby a lamp 115 may be mounted in the lower compartment with its flue extending through said hole, a trough rigidly mounted in said frame and spaced at one end from the end-wall of said frame farthest from said door, the bottom of the trough being concaved and engaging the upper face of said partition whereby the 120 upper compartment is divided through its longitudinal center save at the spaced end thereof, the frame being formed with a central transverse cover strip extending across 125 130

the trough, means for supplying water to the trough, means for discharging water and sediment from the trough, drinking cups removably and replaceably mounted in the trough on opposite sides of the cover strip, means for discharging water and sediment from the bottoms of said cups, the drinking cups being formed with screened openings in their ends communicating with said trough, and apertured covers removably and replaceably mounted on said drinking cups.

2. A sanitary heated stock fountain, comprising a suitable sheet metal frame formed with a horizontal partition whereby the frame is divided into horizontal compartments, said frame being formed with a door in one end of its lower compartment and ventilating ports in said door, said frame also being formed with egress ports in the adjacent end wall of its upper compartment, the partition being formed with a flue-hole adjacent said door and at one side of the center of said partition, whereby a lamp may be mounted in the lower compartment with its flue extending through said hole, a trough rigidly mounted in said frame and spaced at one end from the end wall of said frame farthest from the door, the bottom of the trough being concaved and engaging the upper face of said partition whereby the upper compartment is divided through its longitudinal center save at the spaced end thereof, and means for supplying water to the trough.

3. A sanitary stock fountain comprising a suitable sheet metal frame formed with a horizontal partition whereby the frame is divided into horizontal compartments, a trough rigidly mounted in said frame, said trough being formed with a longitudinal sub-trough in its bottom, the frame being

formed with a central transverse cover strip extending across the trough, means for supplying water to the trough, means for discharging water and sediment from the trough, drinking cups removably and replaceably mounted in the trough on opposite sides of the cover strip, said drinking cups being formed with longitudinal depressions adapted to enter the sub-trough, means for discharging water and sediment from the depressions of said cups, the drinking cups being formed with screened openings in their ends communicating with said trough, and apertured covers removably and replaceably mounted on said drinking cups.

4. A sanitary heated stock fountain, comprising a suitable frame formed with a horizontal partition whereby the frame is divided into horizontal compartments, said frame being formed with a door in one end of its lower compartment and ventilating ports in said door, said frame also being formed with egress ports in the adjacent end wall of its upper compartment, the partition being formed with a flue-hole adjacent said door and at one side of the center of said partition, whereby a lamp may be mounted in the lower compartment with its flue extending through said hole, a trough mounted in said frame and spaced at one end from the end wall of said frame farthest from the door, the bottom of the trough being concaved and engaging the upper face of said partition, whereby the upper compartment is divided through its longitudinal center save at the spaced end thereof, and means for supplying water to the trough.

Signed by me at Marshalltown, Iowa, this twenty-first day of November, 1916.

THEODORE J. BENDLAGE.
